UNITED STATES PATENT OFFICE.

ELMER E. HAUER, OF SPRINGFIELD, OHIO, ASSIGNOR TO ELLIOTT COMPANY, OF PITTSBURGH, PENNSYLVANIA, A CORPORATION OF PENNSYLVANIA.

MULTIPLE-TUBE-CLEANING APPARATUS.

1,218,765.

Specification of Letters Patent.

Patented Mar. 13, 1917.

Application filed May 15, 1916. Serial No. 97,726.

To all whom it may concern:

Be it known that I, ELMER E. HAUER, a citizen of the United States, residing at Springfield, in the county of Clark and State of Ohio, have invented certain new and useful Improvements in Multiple-Tube-Cleaning Apparatus, of which the following is a specification, reference being had thereto the accompanying drawings.

10 My invention relates to tube cleaners and more particularly to a multiple tube cleaner for cleaning tubes in condensers and boilers.

The object of my invention is to provide a simple, efficient and easily operated device 15 having a number of cleaner rods and cutters arranged to simultaneously enter and clean a plurality of tubes.

A further object is to provide means for adapting the device for cleaning tubes 20 spaced different distances apart.

A further object is to provide in combination with a plurality of cleaner rods and cutters a water-box to supply water through the rods to the cutters, the box forming the 25 means of manipulating said rods and cutters.

A further object is to provide a motor having a specially devised casing adapted 30 to carry a plurality of tube cleaners in combination with means to flexibly move and hold the same in operative position for the manipulation of said cleaners in the tubes.

With these and other objects in view my invention consists of the constructions and 35 combinations hereinafter described and set forth in the claims.

In the accompanying drawings which form a part of this specification Figure 1 is an elevation partly in section of a multiple 40 cleaner embodying my invention; Fig. 2 is an end view of same; Fig. 3 is a cross-section on the line 3—3 of Fig. 5; Fig. 4 is a longitudinal section on the line 4—4 of Fig. 6; Fig. 5 is a longitudinal section through 45 the gear case on the line 5—5 of Fig. 3; Fig. 6 is a cross-section on the line 6—6 of Fig. 4; Fig. 7 is a cross-section of a removable gear case similar to the removable gear case shown in Fig. 3 with the cleaner rod journals spaced apart at different distances; Fig. 8 is a cross-section of a water-box showing cleaner rods spaced apart at different 50 distances from those shown in Fig. 6; Fig. 9 is a longitudinal section of an expander to hold the device in fixed relation to the tubes

to be cleaned, and Fig. 10 is a cross-section on the line 10—10 of Fig. 9.

In the drawings 1 represents the casing of a rotary motor of any suitable construction having a driving shaft 2 and provided with 60 inlet hose 3 and exhaust hose 4, the inlet hose leading from the source of supply of the motive agent.

A gear casing 5 preferably formed as a part of the motor casing 1 is provided with 65 an open end having a seat 6.

A removable gear casing 7 has an open end secured to the seat 6 of the casing 5 by bolts 5^a as shown.

A water-box 8 having handles 9 is provided with a supply hose 10 leading from a suitable source of supply. A plurality of blocks 11 have projecting sleeves 12 journaled in the cover 13 and stuffing boxes 14, said cover being secured to the box 8 by 70 screws 15 and holding the blocks and sleeves in place by abutting shoulders 16 of the blocks as shown. Each of the blocks is preferably provided with anti-friction 75 thrust bearings having hardened ring plates 17 and 18 with balls 19 interposed between said plates, said balls being held in place by cages 20.

Hollow cleaner rods 21 rectangular in cross-section extend into the sleeves 12, the 85 inner surface of the sleeves being formed to fit said rods and said sleeves are shrunk thereon to hold them in place. Openings 22 are provided through each of the blocks 11 to admit water to the rods as shown.

The removable gear casing 7 is provided with inwardly extending projections 23 forming bearings, which are preferably provided with bushings 24, in which hubs of gears 25, 26 and 27 are journaled. It will 90 be noted the gears are arranged so that the gear 27 drives each of the gears 25 through the gear 26. To give access for installing the gears within the casing 7 it is provided with a removable cover 28 secured by 100 screws 29.

The motor shaft 2 is journaled within the casing 5 and has a driving gear 30 keyed thereon that meshes with a gear 31 which together with a gear 32 is keyed to a shaft 105 33 journaled in said casing, and the gear 32 meshes with a gear 34 journaled on a stud 35 which meshes with gear 27 of the removable casing 7.

The hollow cleaner rods 21 extend through 110

openings 36 in the casing 7 and through rectangular openings 37 in the gears 25 and 27 and are provided at their outer ends with any suitable form of cleaner head, the type shown having outlets 38 through the heads to discharge water from the hollow cleaner rods.

The means for securing the device in front of the tubes to be cleaned will now be described. It comprises a sleeve 39 split longitudinally as shown at 40 and inserted in a tube, with the flange 41 resting against the outer end of the tube, the inner surface of the sleeve being tapered and a tapered plug 42 adapted to fit the taper of the sleeve has a forwardly projecting straight screw-threaded portion 43 projecting beyond the sleeve. A spindle 44 extends through a bore in the spindle and is provided with a shoulder at one end and a nut at the other end to tighten it in place as shown. Said spindle projects forwardly and has a ring or eyelet 43 at its forward end to engage a hook 46 secured to the casing 5. A handle 47 is adapted to engage the screw-threaded portion of the spindle and by turning the handle against a washer 48 the plug expands the sleeve and tightens it in the tube.

The device being assembled and attached 30 to a pulley block 49 by a hook and eye 50 and said block being suspended by a hook and eye 51 to a carriage 52 having wheels 53 adapted to travel on a rail 54 having suitable supports not shown the device may 35 be moved horizontally and flexibly lifted or lowered in front of a plurality of tubes 55 to an adjusted position and can be flexibly held in such position by the expanding device heretofore described, the inlet and exhaust hose for the motor and the inlet hose 40 for the water-box being of sufficient length to permit of such movement and adjustment.

When the device is in its adjusted position and the motive agent admitted to the 45 motor and the water supply to the water-box, the device is manipulated by the handles 9 of the water-box, the cleaner heads on the ends of the cleaner rods being pushed 50 forward simultaneously into a plurality of tubes, the gears in the gear boxes rotating the rods and water being supplied to the heads through the rods.

Having employed the water-box and gear 55 case 7 with their cleaner rods and gears spaced apart as shown in Figs. 3 and 6 and desiring to clean the tubes of a boiler or condenser requiring a change in these spaces, the gear casing 7 together with the water- 60 box, cleaner rods and gears are removed and another gear case and water-box together with cleaner rods and gears all arranged in like manner but with the cleaner rods differently spaced apart as shown in Figs. 65 7 and 8 are employed, the gear casing 7^a

being adapted to fit and be secured to the seat 6 of the casing 5 so that the gear 34 will mesh with a gear 27^a.

The journals in the water-boxes are lubricated by the water in the boxes and 70 grease can be introduced before attaching the gear casing 7 to the case 5 for the lubrication of the journals in said casings or an oil hole through one or both of said casings can be provided for this purpose.

Having thus described my invention I claim:

1. In a multiple tube cleaner, a motor and a casing having a plurality of gears therein, means to secure the same in a fixed position, 80 a water-box having hollow cleaner rods extending therefrom and movable therewith, said rods being movable longitudinally through journals in said casing into the tubes to be cleaned and adapted to be rotated by said gears and cleaner heads on said rods, substantially as described.

2. In a multiple tube cleaner, a motor and a casing having a plurality of gears therein, means to flexibly carry the same into a fixed 90 position, and means to secure the same in said position, a water-box having hollow cleaner rods extending therefrom and movable therewith, said rods being movable longitudinally through journals in said casing into the tubes to be cleaned and adapted 95 to be rotated by said gears, cleaner heads on said rods and a flexible supply conduit secured to said box, said water-box forming a handle to manipulate said rods, substantially 100 as described.

3. In a multiple tube cleaner, a casing having an open end with a seat, a plurality of casings each having an open end adapted to be secured to said seat, gears in each of 105 said casings, one of the gears in said first named casing being adapted to mesh with one of the gears in any one of the other casings, means to flexibly carry said first named casing and any one of the other casings into a fixed position and means to secure the same in said position, a water-box having hollow cleaner rods extending therefrom and movable therewith, said rods being movable through said last named casing 115 into the tubes to be cleaned and adapted to be rotated by said gears, cleaner heads on said rods and a flexible supply conduit secured to said water-box, substantially as described.

4. In a multiple tube cleaner, a casing formed as a part of a motor and having an open end with a seat and a gear in said casing, a plurality of casings each having an open end adapted to be secured to said seat, 125 a plurality of gears in each of said last named casings, one of which is adapted to mesh with each of the others and another one of said gears adapted to mesh with the gear in said first named casing, a plurality 130

of water-boxes each having journaled there-in and extending therefrom hollow cleaner rods movable therewith, the rods of one box being movable longitudinally through jour-nals in one of said plurality of casings into the tubes to be cleaned and adapted to be ro-tated by the gears therein, said water-boxes and last named casings being arranged in pairs, each pair having their rod journals like distances apart, said distances being different in the respective pairs adapting the

rods to enter differently spaced tubes, cleaner heads on said rods and outlets from said rods adjacent to said heads, substantially as described.

15

In testimony whereof I have hereunto af-fixed my signature in the presence of two witnesses.

ELMER E. HAUER.
